United States Patent Office

Des. 210,769
Patented Apr. 16, 1968

210,769

AIRPLANE SERVICE BUILDING

Dutton Biggs, 800 W. 47 St., Kansas City, Mo. 64110;
Milo S. Ketchum, P.O. Box 28, Old Saybrook, Conn.
06475; and Wayne R. Carlson, 418 Commerce Trust
Building, Kansas City, Mo. 64116

Filed Apr. 24, 1967, Ser. No. 6,813

Term of patent 14 years

(Cl. D13—1)

Des. 210,769

PAGE 2

FIG. 3.

Fig. 4.

FIG. 1 is a perspective view of an airplane service building embodying our design.

FIG. 2 is an elevational view of a side of the building, the other side being a mere image.

FIG. 3 is an elevational view of the building looking toward a corner thereof.

FIG. 4 is a top plan view thereof.

FIG. 5 is an elevational view of a building section looking at the airplane entrance.

FIG. 6 is a side elevational view of the building section.

FIG. 7 is a top plan view of the building sector.

We claim:

The ornamental design for an airplane service building, as shown and described.
